FIRING MECHANISM FOR GUNS.

1,310,043.

Specification of Letters Patent.

Patented July 15, 1919.

Application filed February 3, 1916. Serial No. 75,981.

To all whom it may concern:

Be it known that I, DORSEY F. ASBURY, a citizen of the United States, residing at Washington, District of Columbia, have invented certain new and useful Improvements in Firing Mechanisms for Guns; and I do hereby declare the following to be a full, clear, and exact description of the invention, such as will enable others skilled in the art 10 to which it appertains to make and use the same.

My invention relates to firing mechanisms for guns and is more particularly an improvement of the firing mechanism disclosed in U. S. Letters Patent No. 1,020,849 granted to George L. Smith and myself March 19, 1912.

The objects of my invention are to provide means for operating the lock frame from a shaft having its axis of rotation at an angle to the direction of the sliding movement of the lock frame; to provide means between the lock operator bar and the shaft to positively pull out the wedge, said means being ineffective with respect to the operator bar when the wedge is being pushed home by the firing main spring; to so construct the means between the shaft and the operator bar that same serves as a lock to prevent the 25 wedge from being pushed home while the breech plug is unlocked; to provide a two-point connection between the shaft and operator bar, each of said points of connection being effective to move the bar when the 30 shaft is rotated in one direction and ineffective with respect to the bar when the shaft is rotated in the other direction; to provide a primer guide that can be easily and cheaply made and of a built up construction that 35 will assure that action of every guide being the same and every guide built being usable; to provide an inclined stationary finger or member on the rear end of the magazine bottom to move the bottom primer forward so 40 that the flange on the upper primer cannot get in front of the flange on the bottom primer, said member or finger also serving to move the forward end of the bottom primer into the primer guide; to provide an 45 angular entrance to the magazine whereby the primer moves in and then laterally over in front of a shoulder before going down so that when the primer jumps up due to gun fire or closing of the breech mechanism it

will have to move laterally over before it can 55 come out rearwardly; to provide means whereby the electric connection's contact is assured by the firing lock's mainspring pressure; to locate the electric terminal on the hammer close to the pivot of said hammer 60 to reduce the movement of the electric cable during the operation of the lock; to remove the weight of the electric cable, terminal and terminal fork and its bolt from the firing pin; to limit the feeding stroke of the hammer 65 by a shoulder on the hammer and in the plane of same and which strikes the central part of the receiver, said shoulder adding weight to the hammer, during final locking movement of the wedge, forward of a plane 70 passed through the hammer pivot parallel to the sliding movement of the wedge; to provide a hammer with a preponderance of 75 its mass located, during final locking movement of the wedge, forward of a plane passed through the hammer pivot parallel to the movement of the wedge, so that when the wedge is suddenly stopped at firing position the momentum of the hammer will not 80 rotate the same in the firing stroke direction and explode the primer; to make the side jaws of the hammer of a separate piece to cheapen its manufacture; to provide an extension on the heel of the hammer to prevent the hammer rearing back too far, said 85 extension adding weight forward of the hammer pivot; to extend the receiver up between the prongs of the extractor to form an entering guide for the primer; and to provide elastic means between the hammer and 90 the main spring connection parts to buff or delay the momentum of said parts when the wedge is suddenly stopped at firing position.

In the drawings chosen for the purpose of illustrating my invention the scope whereof 95 is pointed out in the claims.

Figure 1 is a horizontal section of a firing mechanism embodying my invention with certain of the parts in plan and the mechanism shown in locked or firing position; 100

Fig. 2, a rear elevation of the firing mechanism;

Fig. 3, a section on the line 3—3 of Fig. 1;

Fig. 4, an enlarged plan view of a fragment of the mechanism shown in Fig. 1 with 105 the parts in position to initiate feeding of a primer into the primer chamber of the mushroom stem;

Fig. 5, an enlarged horizontal section of what is shown in Fig. 4 with the parts in firing position;

Fig. 6, a section on the line 6—6 of Fig. 4;

Fig. 7, a rear view of the magazine;

Fig. 8, a section on the line 8—8 of Fig. 6;

Fig. 9, a view looking at the forward end of the primer guide, and

Fig. 10, a side view of one of the spring fingers of the primer guide.

In the drawings 10 is the breech plug, 11 the mushroom stem, and 12 the carrier. Rotatably mounted on the carrier 12 is the plug operating shaft 13 which is connected to the plug 10 in the manner set forth in my co-pending application filed Nov. 24, 1914 Serial No. 873755, now Patent No. 1,185,965, June 6, 1916.

The firing mechanism proper comprises a receiver 14 which is detachably mounted on the mushroom stem 11 through the medium of interlocking lugs as fully described in U. S. Patent 1,020,849 granted to George L. Smith and myself March 19, 1912. The receiver 14 is secured in operative position by means of a latch 15 mounted on the lower operator bar guide. The inner face of the receiver 14 is provided with a recess 16 which receives an extractor 17 by which the primers are extracted from the primer seat 18 of the mushroom stem 11. The end of the extractor 17 which is adjacent the mushroom stem 11 is bifurcated to form parallel fingers 19 which constitute a movable base for the primer seat 18. In this instance and in contradistinction from the construction shown in U. S Patent 1,020,849 I extend the receiver up between the fingers 19 of the extractor, as at 20, to form an entering guide 40 for the primers to prevent the latter from moving into the primer seat off center and jamming, such a condition being especially prevalent in the event a primer guide finger remote from the heel of the extractor 45 should be weak and an opposite primer guide finger strong.

A wedge 21 is slidably mounted on the receiver 14 and the extractor 17 is actuated by the sliding movement of this wedge all as is fully described in the said U. S. Patent No. 1,020,849. The wedge 21 carries the magazine 22, which latter is preferably integral with the wedge, and is arranged symmetrically with respect to the primer guide recess 23 through which the primers pass to the primer seat 18. Mounted within the recess 23 is a primer guide A which I construct of a tubular body member 24 seated directly in the recess 23 and secured in place by a screw 25. This member 24 is provided exteriorly with a plurality of longitudinal grooves 26 which are continued through the rear end of the member and receive respectively the inwardly bent ends 27 of spring guide fingers 28, the latter extending through

the bore of the member 24 and converging toward each other in the direction of the primer seat 18. By constructing the guide fingers 28 separately from the member 24 I greatly simplify the manufacture of the primer guide disclosed in U. S. Patent No. 1,020,849 by avoiding delicate machining of a frail structure and the uncertain temper of the parts. Furthermore by providing a primer guide of built up construction I am enabled to make the fingers 28 from steel wire which has been previously spring tempered and thus assure the action of every guide being the same and every one made being usable.

The magazine 22 is provided in its rear end with a primer entrance 29 a portion of the wall of which is inclined to the axis of the magazine, as at 30, while the opposite wall of the magazine is provided with a shoulder 31. By this construction the primer moves through the entrance 29 and then laterally over in front of the shoulder 31 before going down so that when the primer jumps up due to gun fire or closing of the breech mechanism it will have to move laterally over before it can come out rearwardly. I have thus eliminated the possibility of a primer jumping out of the magazine either as a result of gun fire or closing of the breech mechanism. The magazine 22 also embodies a bottom 32 having an integral rearwardly and upwardly inclined finger 33 which acts on the lowermost primer to move same forward so that its flange will lie forward of the flange of the primer next above and so that the muzzle end of the lowermost primer will be entered in the primer exit of the magazine before the feeding of the primer is begun. By thus moving the muzzle end of the lowermost primer into the primer exit I obviate the possibility of the muzzle end of the primer whipping upwardly during feeding and causing a jam or a misfeed.

The firing hammer of the mechanism is indicated generally at B and is pivotally mounted on the wedge 21 at 34. This hammer carries the usual insulated firing pin 35 and primer feeding prong 36, the latter being adapted to move in a slot 37 in the side of the magazine during the operation of feeding a primer. There is pivotally mounted on the magazine 22 a spring actuated hammer latch 38 which serves to hold the prong 36 against executing a primer feeding movement until the magazine registers with the primer seat 18. At such time an arm 39 on the latch 38 cooperates with the receiver to move the latch to release position with respect to the prong 36.

By reference to Fig. 5 it will be obvious that I have constructed the hammer B so that, during final locking movement of the wedge 21, a preponderance of its mass will

be located forward of a plane passed through the hammer pivot parallel to the sliding movement of the wedge. Thus, when the wedge is suddenly stopped at firing position the momentum of the hammer will not rotate same in the firing stroke direction and explode the primer prematurely, although such rotation of the hammer would take place under the conditions specified if a preponderance of its mass was located to the rear of a plane passed through the hammer pivot parallel to the sliding movement of the wedge. I further guard against premature firing of a primer by locating the stop 40, which limits the feeding stroke of the hammer, so that its weight will be forward of the hammer pivot during final locking movement of the wedge, and also by providing an extension 41 on the heel of the hammer to prevent the hammer from rearing back too far, the extension being so located as to add weight forward of the hammer pivot as will be obvious.

25 The hammer B carries the usual stops 42 for engaging abutments 43 on the receiver 14 so that the wedge 21 will remain stationary and in proper position while the hammer is feeding a primer. In this instance 30 I construct the stops 42 from a separate piece of material and then insert and suitably secure same in an opening 42' provided in the hammer for that purpose. By constructing the stops 42 of a separate piece I 35 greatly cheapen the cost of manufacture.

I further provide the firing hammer with a firing handle 44 and an abutment or extension 45 disposed in parallel spaced relation to the handle. Formed in the handle 40 and abutment respectively are alined passages 46 and 47, the latter being of less diameter than the former. A pin 48 is slidably engaged in the passage 47 and is provided with a head having a cylindrical inner 45 end 49 slidable in the passage 46, while the outer end of this head terminates in a ball 50. The purpose of this pin will presently appear.

I will now describe the mechanism for 50 withdrawing and returning the wedge 21 through the medium of the rotation of the shaft 13, it being obvious upon an inspection of the drawings that the direction of the sliding movement of the wedge 21 is 55 at an angle to the axis of the shaft 13. Slidably mounted on the carrier 12 is a cam piece 51 having a recess 52 in its rear face forming shoulders 53 and 54. This cam piece carries a forwardly extending 60 finger 55 having a curved face 56 which merges at one end with the wall 57 of a cam groove 58 formed in the bottom of the cam piece 51, the other wall of the groove 58 being indicated at 59. The shaft 13 carries 65 an arm 60 which is provided at its free end

with a stud 61 adapted to coöperate with the face 56 and walls 57 and 59 as will hereinafter appear. Mounted on the carrier 12 are guide members 62 in which is slideable an operator bar 63, said bar being connected 70 to the wedge 21 in the usual and well known manner so that sliding movement of the bar 63 in a direction away from the receiver 14 will produce a corresponding movement of the wedge 21 while an opposite sliding 75 movement imparted to the wedge will produce a corresponding sliding movement to the operator bar. The end of the operator bar 63 remote from the wedge 21 is enlarged as at 64 to form a shoulder 65 adapted to 80 coöperate with the shoulder 53 of the cam piece 51, it being apparent that the enlargement 64 extends into the recess 52. The enlargement 64 is provided with a passage 66 and an operator 67 connected to the operator bar by a pin and slot connection extends into this passage. The outer end of the operator 67 normally engages the shoulder 54 and is manually disengaged therefrom when it is desired to withdraw 90 and return the wedge 21 by hand all as is fully set forth in U. S. Patent No. 1,020,849. The operator 67 is yieldingly connected with the hammer B by means of a sleeve 68 and a rod 69 slidably mounted in the sleeve. The 95 sleeve 68 is provided with a rounded lug 70 which is seated in a corresponding bearing 71 in the operator. The rod 69 is provided with a suitably shaped bearing 72 which receives the outer end 50 of the pin 48. The 100 sleeve 68 and rod 69 are provided respectively with circumscribing flanges 73 and 74 and a firing spring 75 encircling the sleeve and rod seats at respective ends against these flanges.

As has been previously stated I utilize the pressure of the spring 75 to assure the contact of the terminal of the electric supply cable with the terminal of the conductor leading to the firing pin. To this end I 105 mount on the pin 48 between the handle 44 and the extension 45 terminal insulating washers 76 and 77 and an intermediate washer 78. The washer 76 extends into the passage 46 and is separated from the head of the pin 48 by a felt washer 79 the purpose of which latter will be presently referred to, while the washer 77 seats in an enlarged portion 80 of the passage 47. The electric supply cable 81 has its terminal 115 contact 82 engaged around the washer 78, as is likewise the terminal contact 83 of an electric conductor 84 which leads to the firing pin 35. I am thus enabled to utilize the pressure of the spring 75 to assure contact between the terminals 82 and 83. The construction just described also enables me to locate the terminal 82 of the cable 81 close to the pivot of the hammer and thereby reduce the movement of the cable 81 120 125 130

during the operation of the mechanism. By providing the felt washer 79 between the hammer and the main spring connection parts I am enabled to buff or delay the 5 momentum of said parts when the wedge is suddenly stopped at the firing position and thereby prevent the momentum of such parts being instantly transmitted to the firing hammer.

10 Assuming the parts to be in the position shown in Fig. 1 the withdrawal and return of the wedge 21 during unlocking and locking of the breech is effected as follows. As plug unlocking rotation is imparted to 15 the shaft 13 the stud 61 will coat with the wall 57 of the groove 58 and slide the cam piece 51. During this sliding movement of the cam piece the shoulder 53 will engage the shoulder 65 and cause the operator bar 20 63 to move in unison with the cam piece and thus withdraw the wedge 21. When the wedge is fully withdrawn the stud 61 enters into engagement with that portion of the wall 57 which constitutes in conjunction 25 with the face 56 of the finger 55 the arc of a circle having a radius equal to the distance from the axis of the shaft 13 to the outermost face of the stud 61 so that continued plug unlocking rotation of the shaft 30 will be without effect on the cam piece 51. It will be noted that when the plug 10 is unlocked the arm 60, stud 61 and cam piece 51 serve as a lock to prevent the wedge 21 from being pushed home. During locking 35 rotation of the shaft 13 the stud 61 coats with the wall 59 of the groove 58 and moves the cam piece toward the receiver 14. This movement of the cam piece acts through the shoulder 54, operator 67, sleeve 68, rod 69 40 and main spring 75 to push the wedge 21 home. It will be noted that I provide a two-point connection between the cam piece and lock frame and that when one point of connection is effective to move the lock 45 frame the other point of connection is ineffective. During the withdrawal and return of the wedge 21 the operation of the firing hammer A is identical with that described in U. S. Patent No. 1,020,849, and 50 need not be referred to herein in detail.

It will be noted that when I use the term "lock frame" in the specification and claims I mean the wedge, operator bar and elements carried by these parts.

55 What I claim is:—

1. In a breech mechanism, the combination of a carrier, a plug, a plug rotating shaft, a firing lock frame including an operator bar and an operator, a slidable member 60 between the operator bar and shaft reciprocated by the opening and closing rotation of the shaft, and means whereby the reciprocation of the member will reciprocate the lock frame.

2. In a breech mechanism, the combination of a carrier, a plug, a plug rotating shaft, a firing lock frame including an operator bar and an operator, a slidable member between the operator bar and shaft reciprocated by the opening and closing rotation of the shaft, and means whereby the reciprocation of said member will pull out the lock frame through rigid connections and push said frame home through yielding connections. 65 70 75

3. In a breech mechanism the combination of a carrier, a plug, a plug rotating shaft, a firing lock frame including an operator bar and an operator, and a slidable member between the shaft and operator bar 80 reciprocated by the opening and closing rotation of the shaft, said member operating during movement in one direction directly against the operator bar to pull out the lock frame and during movement in the opposite 85 direction against the operator to push the lock frame home.

4. In a breech mechanism, the combination of a carrier, a plug, a plug rotating shaft, a firing lock frame including an operator bar and an operator, a slidable member between the operator bar and shaft reciprocated by the opening and closing rotation of the shaft, and spaced shoulders on said member one of which acts through rigid 90 95 connections to pull the lock frame out and the other through yielding connections to push the lock frame home.

5. In a breech mechanism, the combination of a carrier, a plug, a plug rotating shaft, a firing lock frame including an operator bar and an operator, a slidable member between the operator bar and shaft reciprocated by the opening and closing rotation of the shaft, and spaced shoulders on said member one of which acts against the operator bar to pull out the lock frame and the other against the operator to push the lock 100 105 frame home.

6. In a breech mechanism, the combination of a carrier, a plug, a plug rotating shaft, a firing lock frame including an operator bar and an operator, a slidable member between the operator bar and shaft reciprocated by the opening and closing rotation of the shaft and having a limited sliding movement relatively to the operator bar, and means whereby the reciprocation of the member will reciprocate the lock frame. 110 115

7. In a breech mechanism, the combination of a carrier, a plug, a plug rotating shaft, a firing lock frame including an operator bar and an operator, a slidable member between the operator bar and shaft reciprocated by the opening and closing rotation of the shaft and having a limited sliding movement relatively to the operator bar, and means whereby the reciprocation 120 125

- tion of said member will pull out the lock frame through rigid connections and push said frame home through yielding connections.
5. 8. In a breech mechanism, the combination of a carrier, a plug, a plug rotating shaft, a firing lock frame including an operator bar and an operator, and a slidable member between the operator bar and shaft
- 10 reciprocated by the opening and closing rotation of the shaft and having a limited sliding movement relatively to the operator bar, said member operating during movement in one direction acting directly against
- 15 the operator bar to pull out the lock frame and during movement in the opposite direction directly against the operator to push the lock frame home.
9. In a breech mechanism, the combination of a carrier, a plug, a plug rotating shaft, a firing lock frame including an operator bar and an operator, a slidable member between the operator bar and shaft having cam faces thereon, an arm on said shaft
- 25 coöperating with said cam faces during opening and closing rotation of the shaft respectively to reciprocate said member, and means whereby the reciprocation of the member will reciprocate the lock frame.
- 30 10. A cartridge guide comprising a tubular member, and a plurality of guide fingers detachably interlocked with the member.
11. A cartridge guide comprising a tubular member, and a plurality of guide fingers formed independently of the member and detachably interlocked therewith.
- 40 12. A cartridge guide comprising a tubular member, and a plurality of guide fingers detachably interlocked with said member and extending through the bore thereof.
13. A cartridge guide comprising a tubular member having grooves therein, and a plurality of guide fingers having a portion thereof respectively seated in said grooves.
- 45 14. In a firing lock for guns, a firing hammer, a firing hammer spring, a firing pin carried by the firing hammer and insulated therefrom, an electric supply conductor connected to the firing hammer and insulated therefrom, an electric conductor connecting the first conductor and the firing pin, and means operated by the pressure of the firing hammer spring to maintain the first and second conductors in contact.
- 55 15. In a firing lock for guns, a pivoted firing hammer, a firing hammer spring, a firing pin carried by the firing hammer and insulated therefrom, an electric supply conductor connected to the firing hammer and insulated therefrom, an electric conductor connecting the first conductor and the firing pin, and means operated by the pressure of the firing hammer spring to maintain the first and second conductors in contact.
16. In a firing lock for guns, a pivoted 65 firing hammer, a firing pin carried by the hammer and insulated therefrom, an electric supply conductor connected to the hammer relatively near the pivot thereof, and a second electric conductor between the first 70 conductor and the firing pin.
17. In a firing lock for guns, a pivoted firing hammer, a firing pin carried by the hammer and insulated therefrom, a firing hammer spring, a firing hammer spring 75 connection carried by the firing hammer, an electric supply conductor leading to the spring connection and insulated therefrom, and a second electric conductor between the firing pin and spring connection and 80 insulated from the latter, the ends of said conductors at the spring connection being clamped together by the firing hammer spring.
18. In a firing lock, a firing hammer, a 85 firing hammer spring, a firing pin carried by the hammer and insulated therefrom, an abutment on the hammer, a plunger having a stem slidable in said abutment, an electric supply conductor having a terminal engaged on the plunger stem and insulated 90 therefrom, a second electric conductor having one terminal connected with the firing pin and its other terminal engaged on the plunger stem for contact with the terminal 95 of the first conductor, and means operated by the pressure of the hammer spring for forcing the plunger in the direction of the abutment to clamp the adjacent terminals of the first and second conductors in contact. 100
19. In a firing lock, a pivoted firing hammer, a firing hammer spring, a firing pin carried by the hammer, and insulated therefrom, an abutment on the hammer, a plunger having a stem slidable in said abutment, an electric supply conductor having a terminal engaged on the plunger stem and insulated 105 therefrom, a second electric conductor having one terminal connected with the firing pin and its other terminal engaged on the plunger stem for contact with the terminal 110 of the first conductor, and means operated by the pressure of the hammer spring for forcing the plunger in the direction of the abutment to clamp the adjacent terminals of the first and second conductors in contact. 115
20. In a firing lock, a receiver, a wedge slidable thereon, means for moving the 120 wedge to and from firing position, and a firing hammer pivoted on the wedge and having a preponderance of its mass during final movement of the wedge to firing position disposed forward of a plane passed 125 through its pivot parallel to the sliding movement of the wedge.
21. In a firing lock, a receiver, a wedge

- slidable thereon, means for moving the wedge to and from firing position, a firing hammer including a primer feeding prong pivoted on the wedge, means for imparting 5 a primer feeding movement to the hammer, and an extension on the hammer engageable with the receiver to limit such feeding movement, said extension being disposed, during final feeding movement of the wedge to firing position, forward of a plane passed 10 through the pivot of the firing hammer parallel to the line of movement of the wedge.
22. In a firing lock, a receiver, a wedge 15 slidable thereon, a hammer pivoted to the wedge, a firing pin carried by the hammer, and an extension on the inner end of the hammer engageable with the receiver to limit rearward movement of the hammer, said extension being disposed entirely on the 20 side of the hammer pivot opposite to the firing pin and forward of a plane passed through the pivot of the hammer parallel to the line of movement of the wedge.
23. In a firing lock, a receiver, a wedge 25 slidable thereon, a firing hammer pivoted on,

the wedge, a firing hammer spring, and a buffer interposed between the spring and hammer.

24. In a firing lock, a receiver, a wedge 30 slidable thereon, a firing hammer pivoted on the wedge, an abutment on the hammer, a plunger having a stem slidable in the abutment, a firing hammer spring operating against the plunger, and a buffering element interposed between the plunger and abut- 35

25. In a firing lock, a receiver, a wedge 40 slidable thereon, a firing hammer pivoted on the wedge, an abutment on the hammer, a plunger having a stem slidable in the abutment, and a firing hammer spring operating against the plunger.

In testimony whereof I affix my signature, in the presence of two subscribing witnesses.

DORSEY FROST ASBURY.
